[57] ABSTRACT

A guide element for baseboard radiation is provided that is interposed between the bottoms of the fins of the radiation heat transfer units and the supporting brackets to hold the units in place and permit them to move noiselessly lengthwise along the brackets during expansion and contraction due to temperature changes. The guide element has portions engaging the heat transfer units to impart stability.

GUIDE ELEMENT FOR BASEBOARD RADIATION

BACKGROUND OF THE INVENTION

1. Field of the Invention

This invention relates to a guide element for baseboard radiation and more particularly to a guide interposed between the fins of the heat transfer units and the mounting brackets for noiseless operation upon expansion and contraction of the heat transfer units.

2. Description of the Prior Art

Baseboard radiation units usually consist of a thin elongated copper tube with a plurality of aluminum fins mounted thereon. The units are supported by brackets with metal shrouding surrounding them and with openings for air passage.

Upon a change in the temperature of the fluid circulating in the tube the tube expands or contracts and causes the fins or the tube to move on their support causing noise and wear of the plates and fins.

Guide elements previously available have been fabricated of metal which does not obviate the noise. Guide elements have also been employed of thin pieces of synthetic plastic material but these were not adequately supported.

The guide element of my invention is interposed between the fins and the mounting plate and held with respect thereto to provide support and reduce noise attendant upon expansion and contraction as well as obviating the other disadvantages of the previously available guide elements.

SUMMARY OF THE INVENTION

A guide element for baseboard radiation is provided which has positive fin support and control permitting movement of the heat transfer units over the supporting brackets with minimum noise and which element is engaged with the units.

The principal object of the invention is to provide a guide element for baseboard radiation which provides silent operation.

A further object of the invention is to provide a guide element for baseboard radiation which is easy to fabricate but is durable in service.

A further object of the invention is to provide a guide element for baseboard radiation that is easy to install.

A further object of the invention is to provide a guide element for baseboard radiation that may be used with a variety of types of baseboard radiation units.

Other objects and advantageous features of the invention will be apparent from the description and claims.

BRIEF DESCRIPTION OF THE DRAWINGS

The nature and characteristic features of the invention will be more readily understood from the following description taken in connection with the accompanying drawings forming part thereof in which:

FIG. 1 is a view in perspective of the guide element of the invention ready for installation;

FIG. 2 is a bottom view of the structure of FIG. 1 on a reduced scale;

FIG. 3 is a fragmentary front elevational view of a portion of a baseboard radiator on a reduced scale incorporating the structure of the invention;

FIG. 4 is a vertical sectional view taken approximately on the line 4-4 of FIG. 3;

FIG. 5 is a vertical sectional view, taken approximately on the line 5-5 of FIG. 4 and

FIG. 6 is a horizontal sectional view taken approximately on the line 6-6 of FIG. 5.

It should, of course, be understood that the description and drawings herein are illustrative merely and that various modifications and changes can be made in the structure disclosed without departing from the spirit of the invention.

10 Like numerals refer to like parts throughout the several views.

DESCRIPTION OF THE PREFERRED EMBODIMENT

15 Referring now more particularly to the drawings and FIGS. 1 and 2 thereof, the guide element 10 as illustrated includes a base 11 of rectangular shape. The guide element 10 is preferably molded in one piece of a material such as asbestos filled polypropylene but any other suitable heat resistant material may be used as desired provided it has a low coefficient of friction with respect to the materials in engagement with it.

The base 11 has two side panels 12 and 14 of rectangular shape and connected at one end by a panel 15 and at the other end by a panel 16. The side panels 12 and 14 are each provided with a longitudinal runner 18 on the underside 19 which runner extends substantially the length of the panel.

The panel 16 has an upright bar 20 extending therewith along with an upright post 21 at each end.

The panel 15 has an upright bar 25 thereon adjacent its rear edge similar to bar 20 and also provided with upright posts 21 at each end.

The rear panel 15 at the edge opposite to bar 25 has a positioning and tube engaging member 27 hingedly secured thereto by hinge 28, which member 27 may be swing to an upright position but when manufactured is formed such as by molding in the same plane as the base 11.

40 The tube engaging member 27 is U-shaped with a base 29 and arms 30 and 31 extending therefrom, the arms being of rectangular configuration and having curved inwardly extending projections 32 at the end opposite the hinge 28 providing an interior opening 33 therebetween.

45 Referring now also to FIGS. 2 to 6, inclusive, a part of a baseboard radiator is illustrated with which the guide element 10 may be used.

The baseboard radiator is of well known type and includes an elongated vertical wall panel 41, an integral top wall 42 extending forwardly therefrom with a hooked upper edge 43 and an integral inclined bottom wall 44 with an integral forwardly extending flange 45.

50 The back wall panel 41 may be secured to the vertical wall of a room (not shown) by suitable fasteners (not shown) such as screws. Mounting brackets 46 are provided, insertable in the engagement with the back panel 41 at spaced locations and secured thereto as desired. The mounting brackets 46 as shown have rear wall sections 47 disposed along the vertical wall 41, integral upper inclined sections 48 with forwardly extending integral upper locking rims 49, and integral forwardly extending lower legs 50 adapted to lie along the bottom wall 44 with their lower margins 51 engaged on the flange 45. The brackets 46 are preferably fabricated of sheet metal and are squeezed into place in the back panel 40 and resiliently held therein.

The mounting brackets 46 may have extending forwardly from one side margin of the rear wall sections 47, an upper supporting arm 52 with a forward inclined margin 53 and curved top edge portion 54 and an intermediate slot 55 with a front supporting edge 56, a bottom margin 57 and a rear supporting edge tongue 58.

The slot 55 with its edge 56, bottom margin 57 and tongue 58 serves for the reception of an elongated damper and divider strip (not shown).

The mounting brackets 46 also each has a lower supporting arm 60 which supports an integral horizontal platform portion 61 at the forward edge of which an upright flange 62 is provided. The flange 62 has a horizontal bracket piece 63 extending therefrom from which a downwardly extending holding tongue 64 extends.

The heat transfer units 70 can be of any desired type but preferably include a central heating or cooling fluid conducting pipe or tube 71 with a plurality of closely spaced vertical sheet metal fins 72 mounted thereon. The fins 72 are shown as rectangular in shape and at the locations at which the brackets 46 have their platform portions 61 directly therebelow, the guide elements 10 are interposed therebetween. The positioning and tube engaging members 27 of the guide elements 10 are disposed between fins 72 and engaged with the pipe or tube 71 with the pipe 71 in the opening 33 and the projections 32 above the pipe. The posts 21 extend vertically upwardly between fins 72 and are restrained therebetween by side vertical portions 73 of the fins 72. The runners 18 rest on the platform portions 61 and are free to move thereon in conjunction with longitudinal or sidewise movement of the heat transfer units 70 attendant upon expansion and contraction.

Elongated front panels 75 may be provided with lower vertical wall sections 76 having lower arcuate flanges 77 for engagement with the holding tongues 64.

The front panels 75 have upper inclined wall sections 78 for engagement with the margin 53 and an upper arcuate flange 79 which hooks over the curved top edge portion 54.

In the installation of the baseboard radiator the back panels 40 are installed first, and are secured to the walls of the room (not shown) by fasteners (not shown). The mounting brackets 46 are then snapped in place with their rims 49 first engaged in hooked edge 43 and then their lower margins 51 swung into engagement with the junction of the flanges 45 and bottom walls 44.

The heat transfer units 70 are then put in place with the fins 72 engaging the posts 21 and the member 27

extending vertically upwardly between two fins 72 and engaged with the pipe 71, with the projections 32 engaging the pipe 71 and retaining the guide element thereon.

5 The heat transfer unit 70 may be connected to adjacent heat transfer units 70.

The front panels 75 are then mounted in position by being hung first over the top edges 54 and then snapped over the holding tongues 64.

10 The heat transfer units 70 and the guide elements are free to move along and across platform portions 61 in accordance with expansion and contraction due to temperature changes and with the movement occurring quietly and without scraping or squeaking noises.

I claim:

1. In baseboard radiation having a supporting bracket and fluid conducting tube and spaced heat transfer fins on said tube, a guide member interposed between said bracket and said fins, said guide member having a portion disposed between a pair of fins and in restrained relation to the fluid conducting tube, said portion including a pair of legs spaced apart at least a diameter of the fluid conducting tube, the ends of said legs being in more closely spaced relation to hold said portion onto the tube, and a base portion spanning a plurality of fins for sliding engagement with said bracket.

2. The combination defined in claim 1 in which said guide member is of unitary construction and is of heat resistant synthetic plastic material.

3. In baseboard radiation having a supporting bracket and fluid conducting tube and spaced heat transfer fins on said tube, a guide member interposed between said bracket and said fins, said guide member having a portion disposed between a pair of fins and in restrained relation to the fluid conducting tube, and a base portion spanning a plurality of fins for sliding engagement with said bracket, said base portion being of hollow rectangular configuration and being horizontally disposed, said base portion having on the bottom thereof a plurality of runners for engagement with said supporting bracket, and having a plurality of posts extending upwardly therefrom disposed between pairs of fins, and said base portion has a guide member extending upwardly therefrom, said guide member having a plurality of spaced legs extending upwardly above the fluid conducting tube providing for the reception of the fluid conducting tube therebetween, and the upper portions of said legs being shaped to hold said guide member against downward movement.
